 Apr. 24, 2017. Comau Introduces e.DO (Year: 2017).*

Primary Examiner — Ian Simmons*Assistant Examiner* — Lauren D McVey(74) *Attorney, Agent, or Firm* — Young Basile Hanlon & MacFarlane, P.C.(57) **CLAIM**

The ornamental design for an educational robot, as shown and described.

DESCRIPTION

FIG. 1 is a perspective view of an educational robot, showing our new design;

FIG. 2 is a right elevation view of FIG. 1;

FIG. 3 is a left elevation view of FIG. 1;

FIG. 4 is a front elevation view of FIG. 1;

FIG. 5 is a rear elevation view of FIG. 1;

FIG. 6 is a top view of FIG. 1; and,

FIG. 7 is a bottom view of FIG. 1.

The broken lines in the drawings depict portions of the article that form no part of the claimed design.

1 Claim, 7 Drawing Sheets(56)
